United States Patent Office

Des. 189,447
Patented Dec. 20, 1960

189,447

CHANNEL SECTION PARTICULARLY FOR USE IN THE CONSTRUCTION OF THE FRAMEWORK OF BUILDINGS

Charles W. Attwood, 4118 S. Wayne Road, Wayne, Mich.

Filed Mar. 28, 1957, Ser. No. 45,478

Term of patent 14 years

(Cl. D13—1)

The figure is a perspective view of a channel section showing my new design, the side and end not shown being like the respective side and end shown.

The characteristic features of my design reside in the longitudinal recesses on opposite sides of the article and in the flanges bordering such recesses as shown.

I claim:

The ornamental design for a channel section particularly for use in the construction of the framework of buildings, as shown and described.
